PICKER STICK LUG OR BLOCK

Arthur P. Lewis, Fairhaven, Mass., assignor to
Roger W. Cutler, Boston, Mass.

Application April 10, 1940, Serial No. 328,976

3 Claims. (Cl. 139—159)

This invention relates to loom pickers and is more especially concerned with the construction and mounting on the picker stick of the block or "lug" which engages the shuttle.

It has been customary for many years in the textile industry to make picker stick lugs of such materials as leather, rawhide, fiber, or various rubber compositions. Because of the nature of the service required of these devices, the rate of wear of the lug itself is relatively rapid, the strains imposed on the means for securing it to the picker stick are extremely severe, and it is, consequently, necessary to replace these lugs at relatively frequent intervals.

The present invention deals especially with these conditions. It aims to improve both the construction of the picker stick blocks or lugs and also the means for mounting them on the picker stick with a view to providing a more serviceable construction, while still maintaining the factor of manufacturing cost within entirely practical limits.

The nature of the invention will be readily understood from the following description when read in connection with the accompanying drawing, and the novel features will be particularly pointed out in the appended claims.

In the drawing:

Figure 1 is a side view showing the upper end 30 of a picker stick equipped with devices embodying the present invention;

Fig. 2 is a front view of the parts shown in Fig. 1;

Fig. 3 is a plan view of said parts;

Fig. 4 is a plan view of a strip from which the blocks are made;

Fig. 5 is a side view showing a slightly different form of picker block and means for securing it in its operative position on a picker stick; and

Figs. 6 and 7 are angular and horizontal sectional views, respectively, of still another form of block made in accordance with this invention, the latter figure showing it secured on a picker stick.

Referring first to Figs. 1, 2, and 3, the construction there shown comprises a lug or block 2 mounted on the upper end of a picker stick 3. The block 2 should be of a yielding, resilient character, so as to afford the necessary cushioning action as the shuttle strikes it and comes to rest while being boxed at one end of its flight without creating any substantial rebound. At the same time it must have the necessary coherence and solidity to propel the shuttle without damaging either it or the picker mechanism.

For this reason I prefer to make the block 2 of some fibrous material united by a resilient binder into a solid block having the desired degrees of hardness, elasticity, and the like. While it is contemplated that the block may be manufactured in various ways, and of a considerable variety of materials, the best method which I have so far devised includes the steps of making a long, narrow strip, such as that shown at 4 in Fig. 4, but having a cross-sectional shape like that of the block illustrated at 2 in Fig. 3. This may conveniently be accomplished by assembling strips of a somewhat open mesh fabric, such as Osnaburg, one upon the other, these strips preferably being cut on the bias and having previously been frictioned and skim coated with rubber prior to being cut into strips. Because considerable heat is developed in one of these blocks during operation, the rubber used should be a heat resisting compound possessing a high degree of adhesion. Raised edges or beads 5—5, Figs. 3 and 4, are formed at the opposite margins of the back of the strip 4 leaving a groove 6 between them to receive the forward edge of the picker stick 3. This may be done, for example, by properly proportioning the volume of material in such a way that the excess of fabric and binder will be forced upwardly during the subsequent molding operation so as to produce these raised edges, or narrower strips of fabric 30 may be so assembled with the others as to produce essentially the same results after molding. Typical cross-sectional dimensions for the strip are seven-eighths of an inch in depth (from front face to the surface of the groove 6) and one and an eighth inches in width. The beads 5 need be only approximately an eighth of an inch in height. The strip should be vulcanized under high pressure, a pressure of at least one thousand pounds per square inch being desirable. 40 The composition and cure preferably are such that the finished strip has a hardness, as measured on a Shore durometer, of somewhere between 90 and 100. For most purposes I have found a value in the neighborhood of 97 seems 45 to give the best results.

Blocks of suitable length, say one and three-eighths inches, for example, are cut from the strip, the cut forming the top surface of the block being made at right angles to the front face and that forming the bottom surface, Fig. 1, being at an acute angle to said face so as to afford the necessary clearance with the raceway.

While the method above described produces a very satisfactory block or lug, it is contemplated 55

that the fiber body may be made up in other ways and that equivalent binders, such as the synthetic rubbers and those synthetic products known as Nylon, Koroseal, and others having the necessary resilience and permanence of adhesion, may be substituted for rubber. Such a block as that above described, however, has the necessary resilience or yield, both radially and longitudinally with reference to the point of impact of the shuttle, and when made of a proper composition and correctly cured, gives a remarkably long life without the laminations splitting away from each other, which has been an important source of failure in prior art blocks or lugs regardless of the materials of which they are made.

As above indicated, an important problem in the production of a satisfactory picker organization consists in the mounting of the shuttle engaging lug or block on the picker stick in such a manner that it will not work loose, will not wear the stick, and will present no projecting surfaces likely to catch yarn. While picker stick lugs or blocks embodying this invention may be secured to a picker stick in a variety of ways, satisfactory arrangements for accomplishing this object will be herein disclosed.

Referring again to Figs. 1, 2 and 3, it will be observed that the block 2 is held against the front face of the picker stick by means of upper and lower U-shaped wire holders 7 and 8, respectively. These two members are similar; and the forward ends of each are hooked into opposite sides of the block 2, while their rearward portions extend around the back of the picker stick and there engage a resilient backer block or pad 9 preferably notched to receive the wires. These holders are made of wire having a high degree of tensile strength and sufficiently stiff so that there is no danger of their hook-shaped ends being bent out of shape under the relatively high working pressure. As shown in Fig. 3, the forward ends of the holder 7 are bent backwardly and inwardly toward each other at angles of approximately 45°, and they extend into holes drilled or otherwise formed in the sides of the block. In addition, the lateral faces of the lug are grooved, as shown at 10, to receive the wires so that they will not project beyond the side faces of the block.

The backer block or cushioning pad 9 may conveniently be made of rubber but should be considerably softer than the block 2 and have a wider range of yield and elasticity. It is molded with a central cut-out at the back, bounded by abrupt shoulders *a* and *b*, Fig. 1, providing seats for the curved ends of the holders 7 and 8. The latter naturally sink into the rubber somewhat and because of this fact and the presence of the shoulders, there is no tendency for them to slip relatively to the pad or backer block itself. Preferably a stiffening element of some appropriate kind, such as a textile cord or a stiffer rubber compound, is molded into the body of this block along the side thereof in contact with the stick 3, where it gives longitudinal stiffness and forms a backbone which is particularly useful in mounting the picker assembly on the stick.

In assembling the parts on the picker stick the holders 7 and 8 are hooked into the opposite sides of the block 2, the backer block or cushioning pad 9 is placed in the loops of the holders, and the upper end of the picker stick then is forced into position between the parts 2 and 9, as shown in Figs. 1 and 3. During this operation

the block is centered on the stick by the groove in its rearward surface. Preferably the front and rearward edges of the picker stick, or the surfaces of the parts 2 and 9 to be engaged with them, are coated lightly with oil or grease, both for the purpose of ultimately reducing the tendency of these parts to slip on the stick after having once been assembled thereon, and also to provide a certain amount of lubrication facilitating the assembly of these members on the 10 picker stick.

It will be observed that when this assembling operation has been completed, the parts 2, 7, 8 and 9 cooperate to encircle the upper end of the picker stick and they are elastically held in 15 position by the engagement of this assembly with the front and rear edges of the stick. In other words, the holder has a resilient floating connection only with the picker stick through the elastic elements 2 and 9. The parts are so dimensioned 20 that the assembling operation requires a very considerable degree of compression of the backer pad or block 9, and a lesser degree of compression of the member 2. This condition is maintained during the life of the picker, and the legs 25 of the holders 7 and 8 are constantly held under tension at all times and notwithstanding the tendency to relieve the compression on the backer block 9 at the instant of impact of the block 2 with the shuttle either in stopping or propelling 30 it. There is, however, a tendency for such impact to move the block 2 upwardly and this tendency can be effectively overcome by any kind of a stop. The arrangement which I prefer is to thread a screw 13 downward diagonally into the 35 picker stick at the upper end of the block, as shown in Figs. 1 and 3, where it holds the block against upward movement.

In using rubber in a picker stick lug there is a tendency for the rubber composition to polymerize and disintegrate at the area of contact with the extreme point of the shuttle. This action seems to occur only at the very small area subjected to maximum pressure. I find that this difficulty can be overcome by forming a hole, 40 such as that shown at 14, in the block 2 so that the material which otherwise would be subjected to this destructive action is removed. I also find that as wear progresses, the hole is deepened 45 in a rearward and upward direction at an angle 50 of approximately 15° with reference to a perpendicular to the front face of the block, and accordingly, I make the hole 14 at this angle or at any other angle necessary to suit specific conditions. It should also be observed that the points 55 of attachment of the hook ends of the holders of the block are entirely outside of the area exposed to the wear of the shuttle point.

It has been found in practice that this construction gives exceptionally satisfactory service. Not only does a block made in the manner above described possess the peculiar combination of elasticity and firmness required for a good picker, but the mounting of the block on the stick seems to overcome completely the objections experienced in using prior art constructions.

It will be seen from an inspection of Fig. 2 that as the hole 14 enlarges, due to the wearing away of its walls by long continued use, the fact that the warp and filling threads of which the plies of fabric in the block are composed are disposed diagonally with reference to the sides of the block, is of very material assistance in maintaining the strength of the reduced dimensions of these walls. In other words, this disposition 75

of the threads, due to the bias cutting of the stock when the strip 4 is made, presents long lengths of threads anchored securely in the thicker portions of the block. This would be true 5 even if the hole 14 became so enlarged as to almost break through into the opposite edges. On the other hand, if the threads were disposed parallel to the edges of the block, the walls at opposite lateral edges would be weakened very 10 materially by such wear, and the horizontal threads could offer very little resistance indeed to lateral spreading, thus bringing practically all of the resistance to this force upon the threads extending parallel to said edges and lying between those edges and the hole. The bias cut construction, therefore, presents a very substantial advantage over the prior art construction. 15 A further and important advantage of this construction is that the parts of the holders no 20 where project beyond the surfaces of the block 2, except at its back where they enter or leave the grooves. This is important in eliminating the presence of parts liable to catch on the yarn and in minimizing the opportunity for lint and fly 25 to collect.

For the foregoing reasons this construction affords a long period of service. When replacement becomes necessary it may be accomplished easily and quickly. At the same time the expense 30 of the entire picker structure compares favorably with that of the less serviceable prior art constructions.

A slight variation of the form of the invention above described is illustrated in Fig. 5. Here the block 2' is like the block 2 except that the holes 35 for receiving the hooked ends of the holders 15 and 16 are inclined in vertical planes instead of in approximately horizontal planes, as shown in Figs. 1 and 3, and these holders extend across the upper and lower ends, respectively, of the block. In other words, the holders are not hooked into the opposite lateral sides of the block 2, but into the top and bottom sides of the block 2'. At the rearward side of the picker 40 stick 3 the holders are engaged with a resilient backer block or cushioning pad 9 as in the construction previously described. This arrangement has the advantage, however, of permitting the holders to lie directly in contact with the 45 opposite lateral surfaces of the picker stick 3' and thus making a very compact arrangement offering little opportunity for accumulation of fly and little danger of catching in the yarn.

Another form of picker stick lug or block embodying the invention is shown at 2" in Figs. 6 50 and 7. Its construction is essentially like that of the block 2 except for the differences required because of modifications in the means for securing this block to a picker stick. The opposite lateral 55 surfaces of this block have grooves, one of which is shown at 17 in Fig. 6, molded or otherwise

formed in them, to receive the apertured ends of a U-shaped sheet metal holder 18, Fig. 7, which straddles the picker stick 3. The holes in the forward ends of the holder are shaped to receive the projections 19-19 which are partially encircled by the grooves 17, and the holder is so biased that its legs or arms tend to spring toward each other. Thus these ends are embedded in and interlocked with the block and when this assembly, including the elastic pad 9, is forced on to 10 the stick 3, it holds the block and the pad firmly against the front and rear surfaces, respectively, of the stick. In this construction, as in those above described, the metal holder is supported in a floating condition relatively to the 15 stick by virtue of the fact that it has no connection with the stick except through the elastic block and pad.

This application is a continuation in part of my pending application Ser. No. 261,752 filed 20 March 14, 1939, for improvements in Loom pickers.

Having thus described my invention, what I desire to claim as new is:

1. A picker stick lug comprising a series of 25 plies of fabric positioned one upon the other in face to face relationship and all extending in a generally parallel relationship to the front face of the lug, and a resilient binding medium securing all of said plies together into a solid but 30 yielding block, the warp and filling threads of said fabric plies lying diagonally with reference to the lateral edges of said block.

2. A picker stick block comprising a series of 35 plies of fabric positioned one upon the other in face to face relationship and all extending in a generally parallel relationship to the front face of the block, said plies being cut on the bias, whereby the warp and filling threads of said 40 fabric plies lie diagonally with reference to the lateral edges of said block, a resilient binding medium securing all of said plies together into a solid but yielding block, the back of said block having a vertical groove therein to receive the 45 front edge of the picker stick and said groove being flanked by parts forming an integral part of the block.

3. A picker stick block comprising a series of 50 plies of fabric positioned one upon the other in face to face relationship and all extending in a generally parallel relationship to the front face of the block, said plies being cut on the bias, whereby the warp and filling threads of said 55 fabric plies lie diagonally with reference to the lateral edges of said block, and a resilient binding material securing all of said plies together into a solid but yielding block, said block having recesses in the opposite sides thereof to receive parts of a metallic holder for securing the block to a picker stick.

ARTHUR P. LEWIS.
